APPARATUS FOR THE APPLICATION OF FINISHING MATERIALS BY DIPPING

Robert F. Wysocki, Lakewood, Ohio, assignor to Pittsburgh Plate Glass Company, Pittsburgh, Pa., a corporation of Pennsylvania

Application September 12, 1949, Serial No. 115,226

3 Claims. (Cl. 91—46)

1

This invention relates to a method of and apparatus for the application of finishing materials by dipping, and more particularly to the construction and operation of dip tanks for the application of industrial finishes such as paints, varnishes, lacquers, enamels and the like.

It is highly desirable to apply finishing materials to articles by dipping because the operation can be carried out rapidly and economically by conveyors which automatically dip the work into and withdraw it from dip tanks containing the finishing material; the operation may be made entirely automatic and there is almost no waste of material. In spite of the economy of dip application, the method is limited in use for various reasons. For instance, while many small objects can be dipped successfully, large areas and involved shapes create problems in obtaining uniform appearance of the finished surface, free from irregularities such as streaking, ribbing, silking, flooding and floating. In some cases such defects of finish appearance are inconsequential, as in the case of industrial shelving, for example; on the other hand, where a high quality of surface is required, as in the case of office equipment such as filing cabinets, desk drawers, legs and the like, dipping has not heretofore been considered feasible.

A general object of the present invention, therefore, is the provision of a method and apparatus for the application of finishing materials by dipping whereby a much better quality of surface finish is obtainable than has been heretofore possible by dipping, and by means of which the approach to optical perfection obtainable may exceed that of application by spraying. Other objects include the provision of methods of applying finishes and obtaining this improved quality of surface which can be carried out simply and economically, and the provision of various forms of relatively simple and inexpensive apparatus for carrying out the method.

In dipping finishes, it is desirable to have the contents of the dip tank homogeneous, particularly the top layer. It is also necessary to have the top layer as free as possible from turbulence and movement with respect to the work. Lack of uniformity of the material in the top layer may result in streaking and in uneven deposits. Turbulence in the top layer may result in frothing of the coating material and the production of layers of uneven thickness with bubbles, sags and the like.

One solution of the problem of maintaining the required homogeneity is to agitate the material in the tank, whereas a solution of the problem of avoiding turbulence in the top layer of the material is to eliminate agitation. Accordingly, most commercial methods involve a compromise, as much agitation as necessary being used to insure a reasonably homogeneous

2

mixture, but the agitation being kept below an amount that will unduly affect the quality of the coating. In many instances, the compromise is unsatisfactory. Frequently, a so-called "float" of oily or unpigmented vehicle, or of different colors will appear in the top layer of the material in the dip tank. The presence of a float frequently causes streaking of the finish and off color spots that impair the uniform appearance of the finish. Various methods of agitation have been employed in an effort to insure homogeneity of the material; circulating pumps, submerged propeller-like agitators and ripple boards for producing small waves on the surface of material in the tank have been used but have not solved the problem or have only partially done so. With these and other prior devices, it has often been impossible to eliminate floating without agitating the tank to such an extent that foaming occurs and bubbles and sags are produced on the work.

The problem in dip finishing is particularly acute when certain recently developed enamels and the like, formulated to produce finishes of exceptionally high quality from a visual standpoint, are employed. These enamels contain additives which improve their sheeting-out qualities and produce surfaces free from streaking and "corduroy" effects when the dipping operation is carried out in a tank in which the material is not greatly agitated and at the same time is substantially homogeneous and free from floating. The difficulty arises from the fact that in some instances, at least, the additives seem to increase the tendency to create floating to such an extent as to render impractical automatic dipping with the usual type of equipment.

According to the present invention, the desired uniformity and homogeneity of the coating material in the dip tank and particularly in the top layer of the dip tank is maintained without requiring excessive agitation by continuously skimming the surface layer of the material in the tank, thus creating a gentle current or flow of the coating material in the upper layers of the finishing material. Skimming removes incipient floats and/or non-homogeneous components in the surface layers of the material in the tank before the floating becomes sufficiently extensive or the non-homogeneity becomes sufficiently great to have an adverse effect on the finish. The surface flow appears to have the effect of continuously supplying to the surface layers of the tank finishing material having the desired homogeneity and quality. This method eliminates the difficulties ordinarily encountered in dip tanks because lack of homogeneity in the coating material ordinarily first appears on the surface of the tank and by constantly replenishing the material in the surface layers by the skimming operation, the separation of the components of

the coating material to an extent sufficient to damage the finish is prevented without excessive or undesirable agitation of the contents of the tank.

Preferably, the skimming operation is carried out in such manner as to create a mild current in the upper layers of the material of the tank in the same direction as the movement of the work through the tank. With this arrangement, while a sufficient current may be maintained in the upper layers of the tank to insure proper quality of the coating material in these layers, the effect of the current is to reduce the relative motion between the work and the finishing material in the important surface layers of the finishing material thus making it possible to approach the ideal condition of withdrawing the work through a calm and relatively stationary surface layer of finishing material.

Preferably, the above skimming operation is carried out by providing a submerged weir in the dip tank and withdrawing the finishing material from a trough behind the weir at such a rate that the finishing material flows smoothly over the weir without frothing or excessive turbulence. The material withdrawn from the trough is preferably returned to the dip tank by a circulating pump and may be filtered before being returned to the tank. The material so withdrawn is returned to the tank through submerged nozzles, outlets, or jets so disposed that the proper movement of the contents of the tank is facilitated in the desired direction. If any supplemental circulation of the contents of the tank is required, to prevent settling for instance, the returned material should pass through the same or similarly disposed nozzles, outlets, or jets. Preferably, the weir is disposed near the exit end of the tank, that is, the end from which the dipped work is withdrawn, in order to create the desired flow in the upper layers in the direction of movement of the work through the tank. Various arrangements of apparatus may be employed to accomplish this result; several such arrangements are shown in the accompanying drawings.

Referring now to the drawings, which are somewhat diagrammatic, Figure 1 is a longitudinal cross section through a preferred form of the dip tank embodying my invention and shows a conveying mechanism for carrying work into and out of the tank; Figure 2 is an enlarged sectional detail showing the nature of the flow of finishing material over the weir; Figure 3 is a plan view of a dip tank similar to the tank of Figures 1 and 2 but embodying a modified form of circulating apparatus; Figure 4 is a longitudinal cross-section of the dip tank shown in Figure 3, the section being indicated by line 4-4 of Figure 3; Figure 5 is a view of a portion of a dip tank embodying a modified form of weir; Figure 6 is a plan view showing a dip tank embodying a weir curved in the horizontal plane; Figure 7 is an end elevational view with parts in section illustrating a weir curved in a vertical plane; Figure 8 is a fragmentary longitudinal section of the end of a dip tank embodying a pivoted adjustable weir; Figure 9 is a similar section of a dip tank embodying a slideable adjustable weir; Figure 10 is a fragmentary perspective view showing the end of a dip tank in which the vertical and horizontal positions of the weir in the tank are both adjustable; Figure 11 is a plan view of a tank in which the weir is disposed along the side of the tank; Figure 12 is a transverse sectional view of the tank shown

in Figure 11, the section being taken along the line 12-12 of Figure 11; Figure 13 is a plan view of a round dip tank having an annular weir; and Figure 14 is a transverse sectional view through the round dip tank, the section being indicated by line 14-14 of Figure 13.

Referring now to Figure 1 of the drawings, reference character 10 indicates a dip tank of generally conventional construction modified to embody the present invention. The tank 10 is rectangular in plan, has straight vertical side walls one of which is indicated at 11 and sloping end walls 12 and 13. A conveyor indicated in general at 15 is disposed above the tank. The conveyor may be of any conventional construction and embodies a plurality of work-supporting units 16 which are moved along the track 17 by any convenient means such as a chain. Each of the units 16 is provided with a hook 18 from which the work W to be coated is suspended, for example, by wires 20. The work may be any article susceptible to coating by dipping, such as the filing cabinet drawers illustrated in the drawing. As is customary, the work is suspended at one corner in order to provide for proper drainage of excess coating material. The track 17 has a sloping entry portion 21, a connecting horizontal portion 22, and a sloping exit portion 23, the sloping portions of the track being approximately parallel to the sloping end walls of the tank. By means of the sloping tracks, the work is dipped gradually into the tank and then removed from the coating material within the tank, the rate of removal being governed by the slope of the exit portion 23 and the rate of travel of the conveyor. These factors are controlled in manners known to those skilled in the art depending on the qualities of the material in the tank in order to give the desired thickness of coating. After leaving the dip tank, the articles may or may not be conveyed through a drying oven, depending upon the nature of the finishing material employed.

The apparatus just described is typical of dip tanks heretofore employed and with which it has been impossible constantly to secure high quality work, the difficulties being due, as noted above, to the presence of floats and the like and other evidence of non-homogeneity in the upper layers of the finishing material in the tank or to effects resulting from excessive agitation of the material in the tank.

In order to eliminate these difficulties, as explained above, the present invention contemplates the provision of a submerged weir 25 which extends from side wall to side wall of the tank and beneath the surface level 26 of the finishing material in the tank. The weir comprises a plate having a horizontal upper edge 27 and lies generally parallel to the sloping end 12 of the tank, the bottom edge of the plate being connected to the end wall of the tank by a narrow plate 28. The weir 25 and plate 28 thus define a trough 30 which receives the finishing material that flows over the weir.

In order to create the desired flow of finishing material in the tank, a circulating pump 31 is provided. The intake of the pump 31 is connected to trough 30 by conduit 32 and to the bottom of the tank by conduit 33, valves 34 and 35 being provided to control the flow through these conduits.

The discharge of the pump leads through filters 36 to discharge conduits 37, 38 and 39 all leading to the tank 10. The return of finishing material

to the tank through these conduits is controlled by valves 40, 41 and 42. A by-pass conduit 44 controlled by valve 45 is connected across the filters 36 so that the tank can be kept in operation while the filters are being cleaned or removed by opening the normally closed valve 45 and closing the valves 46 and 47 in the filter connections.

In operation, the pump is driven at a speed comparable with the speed of pumping in a conventional dip tank of the same size in order continuously to filter the material. The valve 34 is opened sufficiently to withdraw finishing material from the trough 30 at a rate such that the finishing material will flow smoothly over the weir without any frothing or excessive turbulence which might result in the entrapping of air in the finishing material. The appearance of the material as it flows over the weir is indicated in Figure 2. It will be noted that there is no waterfall effect and that the flow is smooth in character. The level of the finishing material above the horizontal edge of the weir and the rate of withdrawal of material from the trough together determine the character of flow. Ordinarily, it is satisfactory to maintain the level of the finishing material from one-half inch to one inch above the weir. This creates a flow in the upper layers of the tank sufficient to maintain the desired flow characteristics in these layers.

If it is desired to withdraw and recirculate more finishing material from the tank than is withdrawn through the conduit 32, the valve 35 is opened to withdraw additional finishing material through the conduit 33. All of the finishing material withdrawn from the tank is recirculated, the return pipes 37, 38 and 39 being arranged as indicated in the drawing to direct the flow of returning finishing materials in such manner as to cause a slow but rather general circulation of material in the tank as indicated by the arrows in Figure 1.

With this arrangement, a surface flow in the direction of movement of the work through the tank is maintained without any excessive turbulence being created in the tank. This circulation maintains the required homogeneity of the material and provides a surface layer which moves in the same direction as the movement of the work as it is being withdrawn from the tank, thus approaching the desired condition wherein the work is withdrawn without substantial relative movement in horizontal directions between the work and the upper layer of finishing material. This arrangement operates satisfactorily in practice and makes possible the consistent production of finishes of higher quality from the standpoint of appearance than have heretofore been obtainable by dipping processes. The apparatus and method are particularly successful when used in connection with organic finishes containing additives that alter the interfacial relationships of the finishes in order to improve sheeting-out qualities of the finishes. These additives seem to have the effect of increasing difficulties with floats in conventional dipping tanks but the difficulties are entirely eliminated with tanks embodying the present invention.

With this and other forms of the invention, material withdrawn from the tank by the dipping operation and losses due to evaporation and the like may be made up by periodically adding material to the tank by any convenient means to maintain the level in the tank substantially constant.

In Figures 3 and 4 a tank generally similar to the tank of Figures 1 and 2 is illustrated, but here the tank 50 is provided with a weir 51 which extends parallel to the end wall 52 to a point spaced a slight distance above the bottom 53 of the tank from which point it extends in a horizontal plane as indicated at 54. The horizontal portion 54 of weir 51 is connected to the bottom 53 of the tank by curved plates 55 which provide a restricted passageway 56 in communication with the chamber 57 formed by the weir.

In order to create circulation within the tank, a propeller type agitator or impeller 58 is disposed within the passageway 55. This is driven by motor 59 and shaft 60, the shaft extending through a stuffing box 61 in the end wall 52. Operation of the propeller 58 creates a circulation in the tank as indicated by the arrows in Figure 4 by withdrawing finishing material from the chamber 57 and discharging it into the tank. This type of apparatus is effective when filtering of the finishing material is not desired; the operation, insofar as the dipping is concerned, is generally similar to that described in connection with Figures 1 and 2.

The arrangement shown in Figure 5 is also similar to that shown in Figures 1 and 2 and may be used with a circulating and filtering system such as shown in Figures 1 and 2. In this form 30 of the invention, however, the tank 65 is provided with an end wall 66, the upper part 67 of which constitutes the enclosed weir. The upper edge of the portion 67 is disposed at the desired level beneath the upper edge of the side walls 68. The 35 side walls extend beyond the end wall 67 as shown, and the trough 69 which receives the finishing material flowing over the weir is constituted by a sloping end member 70 and a horizontal member 71 which extends between member 70 and end wall 66. The finishing material is 40 withdrawn from the trough 69 through the conduit 72 which leads to a pump or other circulating apparatus.

For some purposes it may be desirable to create 45 flows in the surface layers of the tank in lateral as well as longitudinal directions. When this is desired, an arrangement such as is shown in Figure 6 may be employed. The tank 85 is rectangular and the weir 86 is curved so that the 50 surface flow of the finishing material will be longitudinal in the central portion of the tank and partially lateral in the vicinity of the sides of the tank and the side portions 87 of the weir. The trough or chamber 88 which receives the 55 materials flowing over the weir is closed on the bottom by a connecting plate interposed between the weir 86 and the bottom 89 and end 90 of the tank in the manner of the plate 28 shown in Figure 1. A circulating system such as shown in Figure 1 60 may also be employed, the finishing material being withdrawn from the trough 88 through orifice 91, and, if necessary, from the bottom of the tank through orifice 92. The recirculated and filtered finishing material may be returned to the 65 tank through discharge orifices 93, 94 and 95, these orifices being connected with the circulating pump and filter through conduits such as shown in Figure 1.

For some purposes, it may be important to 70 create a greater flow in one portion of the tank than in another. For example, it may be desirable to remove more finishing material from the mid-portion of the tank than from the edges. The arrangement to accomplish this result is 75 shown in Figure 7 wherein the tank 100, which

is generally similar to tank 10 in Figure 1, is provided with a weir 101 having a curved upper edge 102 so that the depth of the material and hence the volume thereof, that flows over the weir is greater at the center than at the edges of the weir. In this form of the invention, the trough for receiving finishing material is enclosed on the bottom by a plate 103 similar to the plate 28 in Figure 1. The circulating system involves a motor driven pump 104 which is preferably of a positive displacement type, filter 105 and suitable conduits and valves arranged in the manner described in connection with Figures 1 and 2.

While the depth of finishing material flowing over the weir may be controlled by regulating the volume of material in the tank, it is also possible to control this depth by adjusting the position of the weir. In Figure 8, the tank 110 is provided with a weir 111 which is hinged as at 112 to the connecting plate 113. An arm 114 secured to the weir 111 near the side of the tank projects above the edges of the tank and is provided with a clamping screw 115 by which it may be clamped to the arcuate segment 116 supported by the end 117 and side 118 of the tank. By this arrangement the height of the weir may be rapidly and accurately adjusted.

A similar arrangement for accomplishing substantially the same result is shown in Figure 9. Here the tank 120 is provided with a weir 121 which is slidably fitted between the transversely extending vertical plates 122 and 123. The weir 121 with the plates 122 and 123 and the horizontal plate 124 define the trough 125 which receives finishing material that flows over the weir. The weir 121 is adjustably supported from the sides of the tank by threaded rods 126 secured to the ends of the weir and provided with wing nuts 127 which engage brackets 128 secured to the side walls 129 of the tank. Although one end only of the weir is shown in the drawing, an identical arrangement is employed at the other end of the weir.

In both Figures 8 and 9 the same general type of circulating apparatus as described in connection with Figures 1 and 2 may be employed. Figure 9 shows a tank with a vertical end wall 130 but it is to be understood that the slideable weir may be used with sloping end walls and the pivoted weir of Figure 8 may be used with vertical end walls. Also, a circulating system such as shown in Figures 3 and 4 may be utilized with devices of these types.

The arrangement shown in Figure 10 embodies a tank 135 in which the weir is adjustable horizontally as well as vertically. The weir 136 forms one side of a box constituting the trough 137, the remaining portions of the box being formed by a rear plate 139, end plates 139 and a bottom plate 140. The box is supported by threaded rods 141 and wing nuts 142 which engage brackets 143 that are slideable along the upper edges of the sides 144 of the tank. Connection from the trough 137 formed by the box 138 to the circulating system is made by pipes 145 and flexible conduit 146 which leads to the end 147 of the tank. Pipe 148 connects the flexible conduit 146 to the circulating system which may be similar to that shown in Figures 1 and 2.

While it is preferred for most purposes that the flow be longitudinally of the tank, for some purposes it may be important to create a transverse flow. For such purposes the arrangement shown in Figures 11 and 12 is provided wherein the tank 150 has a weir 151 extending longitudi-

dinally of the tank and spaced an appropriate distance from the side wall 152. The weir 151 is in the form of a bent plate, the horizontal portion 153 thereof terminating in a downwardly extending flange 154 which is secured to the side wall 152 to provide the trough for receiving the finishing material flowing over the weir. In this modification the finishing material is withdrawn from the trough 155 through a manifold 156 which is connected to circulating pump 157. A filter 158 is provided with appropriate valves and the recirculated material is returned to the tank through orifices 159, 160 and 161 preferably arranged to create circulation within the tank in the direction of the arrows in Figure 12. Thus, in this modification as in the others, the circulation adjacent the bottom of the tank is opposite to that in the upper surface layers.

For small tanks and particularly for hand dipping arrangements, the apparatus as shown in Figures 13 and 14 is desirable. Here the edge 165 of the cylindrical tank 166 constitutes a circular weir, and an annular trough 167 is provided outside of the weir 165 by the annular member 168 which projects above the weir 165 and which has an inwardly extending bottom portion 169 secured to the cylindrical tank wall. The finishing material may be withdrawn at the desired rate from the trough through a plurality of spaced orifices 170 which are connected to the conduit 171 leading to the pump 172 through a manifold 173. The recirculated material is returned to the tank through a centrally disposed orifice 174, thus providing an upward flow of material in the center of the tank and radially outward flow from the center over the weir in the upper layers of the material.

From the foregoing description of various forms of my invention, it will be evident that I have provided a simple and effective method and apparatus whereby the desired characteristics can be maintained particularly in the upper layers of finishing material in dipping tanks. This result can be obtained without agitation of material other than that obtained by circulation of the material in the tank. By so maintaining the desired characteristics in the upper layers of the material, better finishes can be produced by dipping methods than have heretofore been possible. Thus the application of finishes by dipping, which is the least expensive mode of application of finishing material, can be extended to articles requiring such high quality of surface appearance that dipping has not heretofore been feasible. The apparatus is simple and relatively inexpensive, only slight changes being required to incorporate the invention in existing dipping tanks and inasmuch as conventional dipping practice ordinarily requires the circulation of the finishing material in the tank through filters by means of pumps, no additional expensive equipment is required; the only changes necessary to adapt existing dip tanks to the practice of the invention being the inclusion of the weir and changes in the piping of the circulating system.

While several arrangements embodying the invention have been shown herein, those skilled in the art will appreciate that numerous other arrangements can be devised to suit different operating conditions and different designs of tanks all within the teachings of the invention. Therefore it is to be understood that the foregoing description is not given by way of limitation of the invention but rather by way of example and that the invention is not limited thereby, the scope of

the invention being defined in the appended claims.

I claim:

1. An apparatus for applying finishing materials that are subject to the formation of floats, such as paint, enamel, varnish, lacquer and the like to articles, said apparatus comprising an elongated dip tank containing the finishing material, means for creating a gentle current longitudinally of the dip tank in the upper layers of the material and continuously skimming the surface of the tank to prevent the formation of floats thereon, said means comprising a weir submerged beneath the surface of the finishing material in the tank adjacent one end only thereof, said weir defining a chamber separated from the main body of the material in said tank by said weir, pump means including a conduit communicating with said chamber for withdrawing finishing material from said chamber to reduce the level of the material therein as compared to the level of the main body of material in said tank, thereby causing the finishing material to flow across said weir and into said chamber and creating a current in the surface layers of said main body of material longitudinally of said tank toward said weir, conveyor means for dipping articles into the tank near the end thereof remote from said weir, conveying them toward said weir and withdrawing them from said tank near said weir, a conduit communicating with said pump means for returning withdrawn finishing material to said tank, said conduit discharging into said tank through an orifice disposed at a level slightly below the level of the upper edge of the weir and adjacent the end of the tank remote from the weir and opening toward the weir, whereby the discharge of material from said opening contributes to the creation of said current toward said weir, and another conduit communicating with said pump means for returning withdrawn finishing material to said tank, said other conduit discharging into the main body of material in said tank through an orifice near said weir at a lower level than said weir, said orifice being disposed to create a flow of the material along the bottom of the tank in a direction opposite to said current in the upper layers of the material.

2. An apparatus for applying finishing materials that are subject to the formation of floats, such as paint, enamel, varnish, lacquer and the like to articles, said apparatus comprising an elongated dip tank containing the finishing material, said tank having an outwardly sloping end wall, means for creating a gentle current longitudinally of the dip tank in the upper layers of the material and continuously skimming the surface of the tank to prevent the formation of floats thereon, said means comprising a weir submerged beneath the surface of the finishing material in the tank adjacent said sloping end wall, said weir and said sloping end wall defining a chamber separated from the main body of the material in said tank by said weir, pump means including a conduit communicating with said chamber for withdrawing finishing material from said chamber to reduce the level of the material therein as compared to the level of the main body of material in said tank, thereby causing the finishing material to flow across said weir and into said chamber and creating a current in the surface layers of said main body of material longitudinally of said tank toward said weir, conveyor means for dipping articles into the tank near the end thereof remote from said weir, conveying them toward said weir and withdrawing them from said tank near said weir, and a conduit communicating with said pump means for returning withdrawn finishing material to said tank, said conduit discharging through an orifice disposed adjacent said sloping end wall below the level of said chamber, said orifice being directed downwardly along said sloping end wall, whereby discharge of material from said opening creates a flow of the material downwardly along said sloping end wall and along the bottom of said tank in a direction opposite to said current in the upper layers.

the tank near the end thereof remote from said weir, conveying them toward said weir and withdrawing them from said tank near said weir, a conduit communicating with said pump means for returning withdrawn finishing material to said tank, said conduit discharging through an orifice disposed at a level slightly below the level of the upper edge of the weir and adjacent the end of the tank remote from the weir and opening toward the weir, whereby the discharge of material from said opening contributes to the creation of said current, and another conduit communicating with said pump means for returning finishing material to said tank, said other conduit discharging through a second orifice disposed adjacent said sloping end wall below the level of said chamber, said orifice being directed downwardly along said sloping end wall, whereby discharge of material from said opening creates a flow of the material downwardly along said sloping end wall and along the bottom of said tank in a direction opposite to said current in the upper layers.

3. An apparatus for applying finishing materials that are subject to the formation of floats, such as paint, enamel, varnish, lacquer and the like to articles, said apparatus comprising an elongated dip tank containing the finishing material, said tank having an outwardly sloping end wall, means for creating a gentle current longitudinally of the dip tank in the upper layers of the material and continuously skimming the surface of the tank to prevent the formation of floats thereon, said means comprising a weir submerged beneath the surface of the finishing material in the tank adjacent said sloping end wall, said weir and said sloping end wall defining a chamber separated from the main body of the material in said tank by said weir, pump means including a conduit communicating with said chamber for withdrawing finishing material from said chamber to reduce the level of the material therein as compared to the level of the main body of material in said tank, thereby causing the finishing material to flow across said weir and into said chamber and creating a current in the surface layers of said main body of material longitudinally of said tank toward said weir, conveyor means for dipping articles into the tank near the end thereof remote from said weir, conveying them toward said weir and withdrawing them from said tank near said weir, and a conduit communicating with said pump means for returning withdrawn finishing material to said tank, said conduit discharging through an orifice disposed adjacent said sloping end wall below the level of said chamber, said orifice being directed downwardly along said sloping end wall, whereby discharge of material from said opening creates a flow of the material downwardly along said sloping end wall and along the bottom of said tank in a direction opposite to said current in the upper layers.
